(57) **CLAIM**

The ornamental design for an implanting, sensing and reading device, as shown and described.

DESCRIPTION

FIG. 1 is a perspective view taken from a front, right side of an implanting, sensing and reading device according to an embodiment of our design;

FIG. 2 is a perspective, exploded view taken from a rear, right side thereof;

FIG. 3 is a left side elevation view thereof, the right side being a mirror image of the left side;

FIG. 4 is a rear elevation view thereof;

FIG. 5 is a front elevation view thereof;

FIG. 6 is a top plan view thereof;

FIG. 7 is a bottom plan view thereof;

FIG. 8 is a perspective view taken from a front, right side of an inserting unit of the implanting, sensing and reading device of FIG. 1;

FIG. 9 is a left side elevation view thereof, the right side being a mirror image of the left side;

FIG. 10 is a close-up view of portion 10 of FIG. 9;

FIG. 11 is a rear elevation view of the inserting unit of the implanting, sensing and reading device of FIG. 8;

FIG. 12 is a front elevation view thereof;

FIG. 13 is a top plan view thereof;

FIG. 14 is a close-up view of portion 14 of FIG. 13;

FIG. 15 is a bottom plan view of the inserting unit of the implanting, sensing and reading device of FIG. 8;

FIG. 16 is a close-up view of portion 16 of FIG. 15;

FIG. 17 is a perspective view taken from a front, right side of a sensing and reading unit of the implanting, sensing and reading device of FIG. 1;

FIG. 18 is a left side elevation view thereof, the right side being a mirror image of the left side;

FIG. 19 is a close-up view of portion 19 of FIG. 18;

FIG. 20 is a rear elevation view of the sensing and reading unit of the implanting, sensing and reading device of FIG. 17;

and,

FIG. 21 is a front elevation view thereof;

FIG. 22 is a top plan view thereof;

FIG. 23 is a close-up view of portion 23 of FIG. 22;

FIG. 24 is a bottom plan view of the sensing and reading unit of the implanting, sensing and reading device of FIG. 17;

and,

FIG. 25 is a close-up view of portion 25 of FIG. 24.
